UNITED STATES PATENT OFFICE.

FREDERICK D. COOK AND GEORGE A. CONRATH, OF BLAIRSVILLE,
PENNSYLVANIA.

MOLD FOR CASTING HOLLOW WARE.

No. 818,405.

Specification of Letters Patent.

Patented Feb. 27, 1906.

Application filed January 14, 1905. Serial No. 241,039.

To all whom it may concern:

Be it known we, FREDERICK D. COOK and GEORGE A. CONRATH, citizens of the United States, residing at Blairsville, in the county of Indiana and State of Pennsylvania, have invented certain new and useful Improvements in Molds for Casting Hollow Ware; and we do declare the following to be a full, clear, and exact description of the invention; such as will enable others skilled in the art to which it appertains to make and use the same, reference being had to the accompanying drawings, and to the figures of reference marked thereon, which form a part of this specification.

This invention relates to new and useful improvements in molds for casting hollow metal articles.

The invention has for its object the provision of a cheap and effective means for producing hollow castings at little cost, and is particularly adapted for service where a number of like vessels or receptacles are required, especially bath-tubs, sinks, and other hollow or cylindrical bodies.

In the accompanying drawings we have as an illustration shown bath-tub molds embodying our invention, in which—

Figure 1 is a plan view of said mold; Fig. 2, an enlarged transverse sectional view through the same on the line X-X of Fig. 1, and Fig. 3 a perspective view of one of the detachable gate-boxes.

In the practice of our invention we provide for the interior-forming portion from the rim or edge thereof a green-sand mold member or core 1, formed within a drag-flask 2 by the aid of a core-box and arranged upon a bottom board 3, which after being formed is inverted and the core-box removed. The cheek or cope member 4 for the exterior-forming portion from the rim thereof is composed entirely of metal and has formed all the way about its interior, especially its active surface, a space or chamber 5, which through the medium of the pipe 6 communicates with a steam-supply, so that said member may be heated to a temperature approximating 260° Fahrenheit to materially aid in preventing chilling, &c., of the casting to be made. The cheek or cope member is further provided with vertically-disposed pouring-gates 7, which extend and taper upwardly to a point above the top of the mold-line and

have loosely arranged the gate-boxes 8, 55 which member is further provided with an outwardly-converging pop-gate or vent-opening 9.

Preparatory to closing the mold the active surface of the core or drag member is sprayed 60 with a molasses-and-water solution and the interior of the cope or cheek member is coated with a wash of lime or other equivalent. The mold members being thus prepared, the cheek or cope is lowered onto the 65 drag portion and securely clamped thereto, the heat from the cope member being sufficient to effectually bake the entire molasses-sprayed surface of the sand core equally thereover preparatory to pouring the mold, 70 thus forming a "skin-dried" core.

With this form of mold it is necessary to pour the metal therein or cause it to enter at the lowest point. Therefore the pouring-gates have extended above the upper part of the 75 mold and communicate with the flange or rim forming portion by means of runners A, and as the scope or cheek member is permanent in form the gates must be likewise. Furthermore, the rising of the metal in the 80 mold during pouring carries or forces the resultant gases upward, and as they have no means of escape the pop-gate or vent-opening is provided and placed at the highest point.

When the cast has been made, the gate-boxes are struck with a hammer or other implement, causing the sprue collected therein to be broken away from the gates, after which the mold member may be readily lifted 85 from the casting.

Experiments with this form of mold have demonstrated that the castings produced thereby are clean, smooth, and do not require sand-blasting or acid-pickling, as is the case with castings made in the ordinary form 95 of molds, especially those that are to be finished with enamel or paint.

The use of a skin-dried core is preferable, but not absolutely necessary, for, if desired, the core may be baked throughout in the usual way; but the time and expense of producing dry-sand cores are greatly in excess to those of skin-dried character, especially when dried as set forth. Furthermore, a sand core having its active surface hardened not only gives the best results, but is preferable on account of its ability to yield to the contraction of the casting in cooling, which fea-

ture is essential to success where a metal member is employed for forming the exterior.

As we have shown the invention as bath-tub molds, the same has been done as an illustration only, it being evident that other articles—such as sinks, pots, troughs, and a variety of cylindrical bodies—may with correspondingly-shaped molds be made, also that hot air may be used instead of steam to heat the metal member or the same may be heated in an oven, without departing from the spirit of our invention.

Having thus fully shown and described our invention, what we claim as new, and desire to secure by Letters Patent, is—

A mold for casting hollow ware comprising a sand core and a hollow metal member, said sand core and metal member formed with a

space therebetween, said metal member formed with a pouring-gate communicating with said space, said pouring-gate tapering inwardly toward the upper end thereof, and a gate-box formed in its entirety of a mass of material having straight outer walls and formed with an opening tapering inwardly 25 toward the bottom thereof, said gate-box being arranged above said pouring-gate, substantially as described.

In testimony whereof we affix our signatures in presence of two witnesses.

FREDERICK D. COOK.
GEORGE A. CONRATH.
